"Notice of Allowance of Taiwan Counterpart Application," issued on May 2, 2023, pp. 1-6.

Primary Examiner — Shawn T Gingrich*Assistant Examiner* — Justin M. Donaldson(74) *Attorney, Agent, or Firm* — JCIPRNET(57) **CLAIM**

The ornamental design for a semiconductor probe pin, as shown and described.

DESCRIPTION

FIG. 1 is a perspective view of a semiconductor probe pin showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets---
